UNITED STATES PATENT OFFICE.

PAUL E. BERTRAM, OF CRYSTAL LAKE, ILLINOIS.

JOIST-BRIDGING.

No. 918,949.

Specification of Letters Patent.

Patented April 20, 1909.

Application filed June 13, 1908. Serial No. 438,382.

To all whom it may concern:

Be it known that I, PAUL E. BERTRAM, a citizen of the United States, residing at Crystal Lake, in the county of McHenry and State 5 of Illinois, have invented new and useful Improvements in Joist-Bridging, of which the following is a specification.

This invention relates to improvements in joist-bridgings, the object of the invention 10 being to provide a metallic joist-bridging which is simple of construction, strong, durable and efficient in use and inexpensive of production, and which may be quickly and conveniently applied to the joists.

15 In the accompanying drawing illustrating the invention, Figure 1 is a vertical transverse section through adjoining joists showing the application of the bridging. Fig. 2 is a top plan view of the same. Fig. 3 is a 20 perspective view of one of the bridge bars.

In carrying my invention into practice, I provide metallic bridge bars which are employed in pairs and crossed to form a bridge of X - shape between the adjoining joists. 25 Each of these bars 1 is of T-form in cross-section, its flanges 2, constituting one of its elements, and its web 3 constituting its other element, being arranged at right angles to each other. The web element 2 is extended 30 and bent at right angles at one end to form an attaching arm 4 having an opening 5 for the passage of a screw or other suitable fastening device, while the adjacent end of the element or web 3 terminates in line with the 35 inner end of said arm to provide a bearing shoulder 6. The opposite end of the element 2 is properly shaped to form a bearing shoulder 7 which terminates short of the adjacent end of the web 3 which extends beyond the 40 same and is properly shaped to form a penetrating spur or point 8. By this construction a simple, strong, durable and inexpensive type of bridge bar is provided.

In the application of the bars to the joists 45 9 to form a bridging, the bars are arranged between the joists in the manner shown in Figs. 1 and 2, the spur 8 being inserted into one joist, while the arm 4 is fastened by a screw or other securing device 10 to the other 0 joist, the bar being so disposed that the

shoulders 6 and 7 bear directly against the sides of the joists. As a result of this construction and arrangement of the bars, an exceedingly strong and durable bridging is formed. By providing a spur at one end 55 which is adapted to be embedded in one joist and an attaching arm at the other end which is adapted to be secured to the other joist, but a single screw or other fastening is required to be driven or applied and the angular cross-sectional form of each bar and the arrangement of the shoulders 6 and 7 insure the production of a bar of great strength and its application to the joists in a substantial manner. 65

Having thus fully described the invention, what is claimed as new is:—

1. In a joist-bridging, a metallic bridge-bar of angular form in cross section, providing elements arranged at right angles to each other, one of said elements being provided at one end of the bar with a bearing shoulder and at the other end of the bar with a penetrating spur, and the other element being provided at one end of the bar with an attaching portion adjacent to said shoulder and at the other end of the bar with a bearing shoulder adjacent to said spur. 75

2. In a joist-bridging, a T-shaped metallic bridge bar, one element of which is provided 80 at one end with a bearing shoulder and bent at its opposite end to form an attaching arm, and the other element of which is provided with a penetrating spur projecting beyond said shoulder and with a bearing shoulder 85 adjacent said attaching arm.

3. In a joist-bridging, a bridge bar of T-form providing elements arranged at right angles to each other, one of said elements having at one end a bearing shoulder and 90 bent at its opposite end to form an attaching arm, and the other element having at one end a spur projecting beyond said shoulder.

In testimony whereof I affix my signature in presence of two witnesses.

PAUL E. BERTRAM.
